UNITED STATES PATENT OFFICE.

JOSEF KOLB, OF NEUTITSCHEN, AUSTRIA-HUNGARY.

APPARATUS FOR BRUSHING FELT HAT-BODIES.

1,165,516.

Specification of Letters Patent. Patented Dec. 28, 1915.

Application filed July 30, 1913. Serial No. 781,951.

To all whom it may concern:

Be it known that I, JOSEF KOLB, a subject of the Emperor of Austria-Hungary, residing at Neutitschein, in Austria-Hungary, have invented certain new and useful Apparatus for Brushing Felt Hat-Bodies, of which the following is a specification.

This invention relates to apparatus for brushing felt hat bodies, in the course of manufacturing hats.

According to the invention the brush is not moved along a generator of the conical holder of the hat body, as hitherto, but is caused to travel over the surface of the cone in a closed curve on a part of the cone surface, so that the hairs of the hat body are operated upon in all directions and are subjected to a circular brushing action and pointed.

In certain mechanical methods of brushing felt hat bodies, the hairs are brushed flat owing to the brush only performing a rectilinear movement. This method of operation, however, has the disadvantage that the flat hairs tend to adhere to one another both when wet and dry, so that when the hat bodies are dyed the hairs adhere to each other in patches, are difficult to separate and are frequently torn out, resulting in deterioration of the article. The flat hairs also tend to adhere to each other when the hat is in use and the hat has an imperfect polish. According to the present invention the hairs are brushed around and to a point, whereby the adhering together of the hairs is avoided. This is effected by the brush acting in all directions on the hairs, instead of in one direction only, the brush describing an elliptical or oval curve around a part of the cone support, an oval curve being preferable, with the broad part of the curve directed toward the base of the cone. The cone support itself is also rotated, and the hairs acted upon in all directions, are brushed around and pointed so that they do not tend to adhere to each other when wet. This method also allows of more efficient utilization of the brush since the brush operates with the whole of its width, whereas with a brush only moving along a generator of the cone only the center bristles of the brush are utilized.

For performing the operation according to my invention, the brush is arranged on a bar sliding in a guide and moved by an eccentric or the like. The machine is also

provided with means for adjusting the height of the cone support for the hat body, and with means for automatically reversing the direction of movement of the brushes and the cone support and also has a device for automatically stopping the machine after the completion of a predetermined number of revolutions.

The invention is illustrated in the accompanying drawing, which shows a machine for carrying the improved method into effect and in which—

Figure 1 is a front view of the machine partly in section, and Fig. 2 a plan view thereof, also partly in section. Fig. 3 is another sectional plan view of the machine frame showing details. Fig. 4 is a vertical section of the machine. Fig. 5 is a side view of the gear for automatically stopping the machine. Fig. 6 is a longitudinal section of the brush. Fig. 7 shows a detail. Fig. 8 is a longitudinal section of part of the brush actuating gear, and Fig. 9 shows a detail of the gear shown in Fig. 8.

The machine comprises in the main the conical support for the hat body, the brush carrier, and mechanism for automatically reversing the direction of movement of the machine and for stopping the latter after a predetermined time.

The support 1 for the hat body is mounted on a vertical shaft 2, which is driven from the shaft 5 by bevel wheels 3, 4 said shaft 5 receiving motion from the main driving shaft 6 by means of a chain 7. The chain 7 is mounted on sprockets 8, 9, 10 the sprocket 9 on the spindle 11 driving the brushing device and the reversing gear. The shaft 2 is arranged to slide vertically in the frame 12, and is carried in a foot bearing 13 by two bars 14, which are supported by chains 15 passing over chain-wheels 16 and carrying a balance weight 17. The two chain-wheels 16 are mounted on a shaft 18, which is journaled in the frame and is adapted to be turned with the aid of gearing 19 and a crank 20, for the purpose of raising or lowering the conical support. The crank is provided with means for locking it, such as a pawl and ratchet wheel or a spring loaded pin arranged to engage in a socket in the frame, and hold the cone support 1 in position.

A plurality of brushing devices (three in the machine shown) are provided for each hat body. The brushing devices are driven

by the spindle 11, which drives by bevel gear 21, a shaft 22, the latter driving by bevel gears 23, 24, two shafts 25, 26, on which are mounted the brushing devices, and from one of which, for instance, the shaft 25, another brush shaft 30 may be driven with the aid of shaft 27 and bevel gears 28, 29.

The shafts 22, 25, 26, 27, and 30 are mounted on an annular frame 31 encircling the cone support 1.

On each of the shafts 25, 26 and 30 there is fixed a worm 32 (Fig. 8) meshing with a worm-wheel 33, the shaft 34 of which carries an eccentric or crank-disk 35, a pin on the latter carrying by means of a ball joint 36 a brush holder 37 (Figs. 1 and 6). The eccentrics or crank disks of the brushes are off-set with respect to each other, so that the several brushes do not all move upward together. To prevent the whole weight of the brush carrier from resting on the shaft 30, the bow 38 carrying the worm-wheel 34 is mounted on annular supports 39 of the bearings 40, 41, (Fig. 8), which take the weight.

The bearing 40 is provided with a flange 42 having a curved slot (Fig. 9) which enables the bow 38 and consequently the brushing device, to be adjusted for different sizes of supports 1.

The brush carrier comprises a frame 37 in which the brush 43 is inserted, springs 44 being interposed between the brush and frame (Fig. 6) in order to provide the brush with a certain amount of play which is necessary in view of the wooden support 1 tending to warp and lose its shape under the action of the hot water used during the brushing operation; uniform operation of the brush is thus insured. The brush may also be held up to its work by weights instead of by the springs.

The brush frame carries a rod 45 working in a guide 46. The guide 46 is carried by an arm 47 in which it is free to rotate. As the rod 45 is guided at one part and has to follow the movements of the eccentric, the brush carrier and brush consequently describe an elliptical or oval path which insures that the hairs are brushed in all directions. The rod 45 also carries a pivoted head brush 48, which performs a curved but smaller movement. The eccentric 35 operating the brushes makes about 20 revolutions per minute and the shaft 2 about 40 revolutions per minute.

To allow of reversing the direction of rotation of the hat support and brush carrier, worm gearing 49, 50 (Fig. 5) is provided, which is driven from the spindle 11 and is carried by a bracket 51 cast on the stand or otherwise secured, the part of the bracket forming the bearing 51¹ for the shaft 52 of the worm wheel also serving as

a pivot for a weighted lever 53, which rocks between two stops 54 of a belt-fork bar 55. The latter is arranged to slide horizontally in the arms 56 of the stand, and is adapted to move the driving belt of the machine and the crossed belt 58 from the fixed pulley 59 to one of the two loose pulleys 60, 61. The weighted lever 53 is moved by a crank arm 62, which is keyed to the end of the worm-wheel shaft 52, and as the worm-wheel rotates strikes against an abutment 63 fixed to the weighted lever and moves the latter past its vertical position, whereupon the lever drops by gravity and shifts the belt fork bar.

In order to enable the belt fork to be operated by hand for the purpose of throwing the machine out of gear, one end of the belt fork bar 55 is linked by a double armed lever 64, and by a bell crank lever 65 connected to the latter, to the rod 66, which is guided on the frame of the machine and is provided on its underside with a notch 67 (Fig. 5).

Parallel to the rod 66 is a shaft 68 provided at one end with a hand crank 69, the latter working over a graduated scale 70. On the other end of the shaft 68 is mounted a ratchet wheel 71 (Fig. 3) engaged with a pawl lever 72 (Fig. 7). The latter is connected by a link 73 to the lever 65 and is automatically moved after every second reversal of the belts so that the lever 72 moves the ratchet-wheel and with it the shaft 68 to the extent of one tooth. Fixed to the shaft 68 is an arm 74, which moves with the shaft until it arrives underneath the rod 66, and abutting against the latter raises it. If, then the weighted lever is rocked at the next shifting of the belts, the said weighted lever only moves until the rod engages with its notch the arm 74. In this manner the belt shifting gear is locked, this taking place when both belts are on the loose pulleys, so that the machine is stopped. As the arc to be described by the arm 74 is regulated beforehand by adjusting the shaft 68 by means of the crank 69, one is able to adjust the number of reversals at every operation, or the period of treatment of a hat body.

It will be obvious that one gear may be arranged to stop a number of brushing machines and one machine can be provided with several sets of hat bodies with appurtenant sets of brushes. The machine hereinbefore described is adapted for two sets of hat bodies, only one being shown for the sake of clearness of illustration.

What I claim as my invention and desire to secure by Letters Patent of the United States is:

1. In a machine for the purpose set forth, the combination, with a rotatable support for the hat body, of a brush holder and means adjacent said support for moving

said brush holder in an orbit whereof the axis intersects the axis of rotation of said support.

2. In a machine for the purpose set forth 5 the combination with a rotatable support for the hat body of a rotatable brush holder, means adjacent said support for moving said brush holder in an orbit whereof the axis intersects the axis of rotation of 10 said support, a rod fixed to said brush-holder, and a rotatable guide wherein said rod is slid able.

3. In a machine for the purpose set forth 15 the combination, with a rotatable support for the hat body, of a rotatable brush holder, means adjacent said support for moving said brush holder in an orbit whereof the axis intersects the axis of rotation of said support, a rod fixed to said brush-holder, a 20 rotatable guide wherein said rod is slid able, and a second brush holder pivoted to said rod.

4. In a machine for the purpose set forth, 25 the combination, with a rotatable hat support, of a shaft having a crank, a bearing for said shaft, a worm wheel fixed to said shaft, a worm shaft engaged with said worm wheel, a bearing for said worm shaft, and a brush holder carried by said crank, 30 said crank moving said brush holder in an orbit whereof the axis intersects the axis of rotation of said hat support.

5. In a machine for the purpose set forth, 35 the combination, with a rotatable hat support, of a shaft having a crank, a bearing for said shaft, a worm wheel fixed to said shaft, a worm shaft engaged with said worm wheel, a bearing for said worm shaft, a brush-holder, a ball and socket connecting said brush holder to said crank, the latter moving said brush holder in an orbit whereof the axis intersects the axis of rotation of said hat support, and means for varying the inclination of said worm shaft 40 bearing to the axis of rotation of said hat support.

6. In a machine for the purpose set forth 45 the combination, with a rotatable support for the hat body, of a brush holder, and means adjacent said support for moving said brush holder in an orbit whereof the axis intersects the axis of rotation of said support, said brush-holder having means for resiliently thrusting a brush toward 50 said hat support.

7. In a machine for the purpose set forth, 55 the combination of a rotatable hat support, an axially adjustable vertical shaft carrying said support, a support for said shaft, a sprocket wheel, a chain engaged with said sprocket wheel and attached at one end to 60 said shaft support, a balancing weight at-

tached to the other end of said shaft, and means for locking said sprocket wheel.

8. In a machine for the purpose set forth, 65 the combination of a hat support, means for rotating said support, a brush holder, means for moving said brush holder in an orbit whereof the axis intersects the axis of rotation of said hat support, means for intermittently reversing the direction of rotation of said hat support and the direction of travel of said brush-holder, and means for stopping said rotation and travel after a predetermined number of reversals. 75

9. In a machine for the purpose set forth, 80 the combination of a hat support, means for rotating said support, a brush holder, means for moving said brush holder in an orbit whereof the axis intersects the axis of rotation of said hat support, means for intermittently reversing the direction of rotation of said hat support and the direction of travel of said brush-holder, and means for stopping said rotation and travel after a 85 predetermined number of reversals, said reversing means comprising a weighted lever and means for intermittently rocking said weighted lever past a position of equilibrium. 90

10. In a machine for the purpose set forth 95 a rotatable support for the hat body, a brush holder and means for moving said brush holder in a closed curve over the said hat body holder.

11. In a machine for the purpose set forth a rotatable felt support, a brush actuating shaft, a worm wheel fixed to said shaft and a support for said shaft, a worm shaft engaged with said worm wheel, a bearing for 100 said worm shaft said bearing carrying the said support of the brush actuating shaft.

12. In a machine for the purpose set forth 105 the combination of a support for the felt hat body means for rotating said support, a brush holder, means for moving said brush holder in a closed curve over the said support, means for intermittently reversing the direction of rotation of said hat support and the direction of said brush holder and 110 means for stopping said rotation and travel after a predetermined number of reversals, said stopping means comprising an adjustable locking arm with means for moving said arm step by step into engagement with 115 rods governing the driving means.

In witness whereof I have signed this specification in the presence of two witnesses.

JOSEF KOLB.
